FLOOR CONSTRUCTION

Filed March 6, 1931

UNITED STATES PATENT OFFICE

JESSE R. BOWMAN, OF NEWBURYPORT, MASSACHUSETTS

FLOOR CONSTRUCTION

Application filed March 6, 1931. Serial No. 520,590.

This invention relates to a plastic floor construction and to a method of making the same.

One object of the invention is to provide a novel and improved construction of plastic floor, and more particularly a novel and improved construction of a terrazzo floor which may be economically laid, is durable and resilient, and capable of resisting cracking when the building or foundation settles.

A further object of the invention is to provide a novel and improved method of making the improved floor by which economies in both the material and labor cost may be effected.

With these general objects in view, the invention consists in the floor construction and in the method of making the same hereinafter described and particularly defined in the claims at the end of this specification.

In the drawing illustrating the preferred embodiment of the invention, Fig. 1 is a side elevation of one of the mold forming strips used in producing the present construction of floor; Fig. 2 is a similar view of one of the cross strips used in conjunction with the strip shown in Fig. 1 for forming the molds; and Fig. 3 is a sectional view illustrating a portion of a floor embodying the present invention.

In general the present invention contemplates the production of a plastic floor, which while adapted for installation over any type of foundation member is particularly adapted to be laid over concrete or a similar foundation member, and the invention contemplates the production of a floor and preferably a floor of the type of a terrazzo floor in which liability of the molded terrazzo or other sections of the floor becoming cracked when the building or foundation settles is reduced to a minimum. The invention also contemplates a construction of and a method of constructing a floor by which important economies in both the material comprising the molds and the labor involved in laying the floor may be secured.

Referring now to the drawing, which as above stated illustrates the preferred embodiment of the invention, the individual molds

for forming the individual molded blocks making up the terrazzo or other plastic floor are in accordance with the present invention formed by two sets of vertical mold forming strips 1 and 6, and for purposes of description the vertical mold forming strips 1 will be hereinafter referred to as the longitudinal strips and the mold forming strips 6 will be hereinafter referred to as the cross strips. As herein shown the longitudinal mold forming strips 1 comprise sheet metal strips, preferably of zinc, brass, copper or nickel silver, provided with a plurality of slots or openings 4 for the reception of end tabs or ears 8 projecting from the opposite ends of the cross strips 6. Both strips 1 and 6 may and preferably will be provided with anchoring lugs 2 projecting laterally from opposite surfaces of each strip and which may conveniently be stamped from each strip and bent outwardly into a substantially horizontal position.

In laying a terrazzo or similar floor over a foundation member 20, I apply over the foundation a layer 22 of concrete or similar plastic, and when the foundation member comprises concrete or other non-flexible material, it is preferred to incorporate fibrous material such as asbestos fiber into the concrete layer 22 to provide a more or less resiliency layer 22. Before the plastic layer 22 has become hardened or set, a plurality of the longitudinal strips 1 are pressed down into the same until each strip projects above the surface of the layer 22 a predetermined distance, such as three-fourths of an inch. The strips 1 are arranged in rows preferably extending across the floor, and the rows are spaced apart to correspond to the size of the blocks or individual molded sections of the finished floor. In order to firmly anchor the strips 1 in the plastic layer 22, the bottom of the strips are provided with anchoring means, herein shown as comprising a plurality of tabs 26 projecting from opposite sides of the lower portion of the strip 1 and conveniently the tabs 26 may be formed by stamping out V-shaped sections from the lower portion of the strip 1 to leave a plurality of V-shaped openings 28 therein between which the tabs 26 may be formed by

bending the tabs outwardly into the position shown in Figs. 1 and 3. In the operation of laying the floor after the strips 1 have been pressed into the plastic layer 22 before the latter has set, and after the plastic layer has become set, the remaining sides of the molds are formed by the cross strips 6 which are flexed and snapped in between adjacent rows of the strips 1 with the end tabs 10 or ears 8 projecting through the slots 4 in the strips 1.

In order to prevent the absorption of the water from the concrete or other plastic used in producing the molded blocks or sections 15 of the floor, by the underlying plastic layer 22, I prefer to waterproof the bottom of the molds, and this may be best accomplished by producing the layer 30 of waterproofing such as fluid asphalt over the plastic layer 22 and 20 before the cross strips 6 have been snapped in place. In this manner such waterproofing 30 may be conveniently laid up and down the several alleys formed by the spaced rows of the strips 1. After the waterproofing 30 has been laid, the concrete or other plastic for 25 forming the molded blocks 32, such as a known terrazzo mix, may then be poured into the individual molds formed by the cooperating strips 1 and cross strips 6. In order to 30 anchor both the strips 1 and 6 to the molded blocks 32, the anchoring members 2 are preferably stamped from each strip and bent outwardly in opposite directions therefrom, 35 preferably into a substantially horizontal position.

The present construction of floor lends itself particularly to the production of any desired design in the finished floor, and the individual blocks 32 may be made of any desired 40 size or shape. The floor may be economically laid and when completed the liability of cracks forming in the molded blocks or sections 32 of the floor is reduced to a minimum by reason of the more or less resilient underlying layer 22 of plastic and the absence of a bond between the molded blocks 32 and the foundation.

While the preferred embodiment of the invention has been herein illustrated and described, it will be understood that the invention may be embodied in other forms and in other methods within the scope of the following claims.

Having thus described the invention, what 55 is claimed is:-

1. In a flooring construction, in combination, a foundation member, a plurality of mold forming strips vertically arranged, said strips being secured to said foundation member, a plurality of cross strips cooperatively associated with the aforesaid mold forming strips and forming a plurality of individual molds therewith, plastic material filling said molds, and means for preventing bonding of 60 said plastic material and said foundation 65

member whereby the blocks formed by the plastic material are restrained from movement only by the engagement with said strips, said strips being constructed and arranged to permit a floating action of the blocks retained thereby. 70

2. In a flooring construction, in combination, a foundation member, a plurality of mold forming strips vertically arranged and having their lower ends secured to said foundation member, a plurality of cross strips associated with said mold forming strips and forming a plurality of individual molds therewith, plastic material filling said molds and forming individual blocks therein, means interposed between the blocks and foundation member for preventing surface bonding whereby said blocks are floatingly secured to said mold forming strips and said strips being constructed and arranged to permit said floating action of the blocks. 80

3. In a flooring construction, in combination, a foundation member, a plurality of mold forming strips vertically arranged and having their lower ends secured to said foundation member, said strips being arranged in rows spaced apart, a plurality of cross strips engaging the aforesaid mold forming strips and secured in place thereby and forming a plurality of individual molds therewith, plastic material in the form of blocks filling said molds, and means for preventing surface adhesion between the foundation and the plastic material forming the blocks, said strips being resiliently constituted, whereby to permit floating movements of said blocks. 90

4. In a flooring construction, in combination, a foundation member, a plurality of mold forming strips vertically arranged and having their lower ends secured to said foundation member, a plurality of other strips loosely connected with the aforesaid mold forming strips to be secured in place thereby and forming a plurality of individual molds therewith, plastic material in the form of blocks filling said molds, and means for preventing surface adhesion between the foundation member and said plastic material forming the blocks, the aforesaid loose connection between said strips permitting weaving or floating action of the blocks. 100

5. In a flooring construction, in combination, a foundation member of plastic material, a plurality of mold forming strips anchored in said plastic material and projecting vertically above the same, a plurality of cross strips secured to the aforesaid mold forming strips to form therewith individual molds, plastic material in the form of individual blocks filling said individual molds, and means for preventing surface adhesion between said plastic foundation member and the molded blocks whereby the blocks are maintained in place only through the anchorage of the mold forming strips, said strips 110

being constructed and arranged so as to permit the blocks to be floatingly disposed upon the foundation member.

5 6. In a flooring construction, in combination, a foundation member, a plurality of mold forming strips vertically arranged and having their lower ends secured to said foundation member, other strips of less height than the aforesaid mold forming strips secured to the foundation member through the medium only of said mold forming strips, means for preventing surface adhesion of the molded blocks to the foundation member, said strips being constructed and arranged whereby to permit the blocks to be floatingly disposed upon the foundation member.

10 7. In a flooring construction, in combination, a plastic foundation member, a plurality of mold forming strips embedded and anchored in said foundation member and projecting vertically above the same, a plurality of cross strips cooperating with the aforesaid mold forming strips to form a plurality of individual molds, plastic material 15 filling the molds, and means for preventing bonding of the plastic material to the foundation member, said mold forming and cross strips being constructed and arranged whereby to permit floating movements of the plastic material retained thereby and provided with means for securing the molded plastic material to said strips.

20 8. In a flooring construction, in combination, a foundation member, a plurality of 25 separate molded blocks of plastic material, metal spacing strips separating the individual molded blocks and to which said blocks are secured, means for securing said spacing strips to the foundation, and means for preventing surface adhesion between said blocks and the foundation member and said strips being so constituted whereby said blocks are floatingly disposed upon the foundation member.

30 45 9. In testimony whereof I have signed my name to this specification.

JESSE R. BOWMAN.
